UNITED STATES PATENT OFFICE.

SAMUEL E. HALSEY, OF EVERETT, WASHINGTON.

TYPE-CLEANING DEVICE FOR TYPE-WRITING MACHINES.

No. 811,894.

Specification of Letters Patent.

Patented Jan. 30, 1906.

Application filed March 24, 1905. Serial No. 251,888.

To all whom it may concern:

Be it known that I, SAMUEL E. HALSEY, a citizen of the United States, residing at Everett, in the county of Snohomish and State of Washington, have invented a new and useful Improvement in Type-Cleaning Devices for Type-Writing Machines, of which the following is a specification:

My invention relates to type-cleaning devices for type-writing machines, its object being to provide a simple, cheap, and efficient device of the character specified and one which can be readily attached to or detached from a type-writing machine and also secured to the frame of the machine when not in use.

To these and other ends my invention consists of certain novel features of construction, arrangements of parts, and combinations of devices, as will be hereinafter fully described, and pointed out in the claims.

In the drawings, in which like reference characters indicate corresponding parts, Figure 1 is a fragmentary perspective view of a number of parts of one character of type-writing machine, illustrating my invention in its application thereto. Fig. 2 is a longitudinal section showing the interior of the casing and the actuating means for operating the brush. Fig. 3 is a section taken on line 3-3 of Fig. 2. Fig. 4 is a perspective view of the rear wall of the casing. Fig. 5 is a view, partly in section, showing an extensible form of device. Fig. 6 is a top view of the same device. Fig. 7 is a view showing the improved device stowed in one of the standards of the type-writing frame. Fig. 8 is a sectional view showing the device held inside the leg of frame of type-writer by means of an elastic cord and hook and eye.

I have shown my device applied to a Remington machine, and sufficient of such machine is shown to illustrate my invention in its application thereto.

The frame of the machine comprising the corner-posts 1 and top plate 2 has mounted therein by hangers 3 a circular series of type-bars 4, which are connected by links 5 to the usual key-levers. (Not shown.) Extending upwardly from the top plate 2 are risers 6, which support one of the transverse rods 7, upon which the carriage is supported and guided in its movement from end to end of the machine.

8 is the ribbon-plate, which carries the ribbon 9, said ribbon extending across the type-well 10.

11 is a shift-rail which constitutes a bearing for the carriage at the front side thereof and is used to shift the platen and its frame 60 for upper and lower case writing. Connected to the shift-rail at its center is a block 12, which extends downwardly and forwardly from the shift-rail and is provided at its forwardly-projecting portion with a pointer 13, 65 which co-operates with the indices on the usual carriage-scale.

14 represents the casing of the type-cleaning device and consists of the circular box, having a front wall 15 and a rear wall 16. The 70 front wall is usually made integral with the circular casing, while the rear wall is made removable therefrom. The casing has an elongated slot 17 in its lower face extending from front to rear. The rear wall 16 of the casing has at its lower edge an angular rearwardly-projecting tongue 18, which fits within the slot 17 and then extends rearwardly under the cross-bar 14^a, as shown in Figs. 2 and 6. To the upper edge of rear wall 16 is a spring 80 latch member 19, extending forwardly over the upper surface of the casing and terminating in a downwardly-projecting lip 20, which fits against the front wall of the casing, thus retaining the rear wall 16 in position and also 85 permitting the same to be readily removed.

21 is a rod or bar extending forwardly from the front wall of the casing, said bar being made with a downwardly-offset bend 22 near its front end. The front end 23 is widened 90 and its edge slotted, as at 24, said slot being to admit the block 12 on the shift-rail and prevent lateral movement of rod or bar 21 while in use.

25 is a brush having stiff bristles, said 95 brush being rigidly secured to a spirally-grooved shaft 26 near one end. Said shaft 26 extends through an opening in the front wall of the casing immediately below the bar 21 and into an opening made in the downwardly-offset bend 22, said shaft being also pointed at each end to form pintles 26^a.

28 is a nut provided with the curved wings 29 on each side forming finger-pieces. The nut 28 is grooved or cut out on its upper surface 105 so that it may slide with respect to bar 21 and be guided thereby. The bore of nut 28 is spirally threaded and fits snugly on the spiral

groove of the shaft 26, said nut when moved back and forth causing the spirally-grooved shaft to revolve in either direction.

30 is a spirally-coiled spring surrounding the shaft 26 and bearing at one end against nut 28 and at its opposite end against the offset bend 22 in bar 21.

The slot 17 in the lower face of the casing has a downwardly-projecting flange 17^a surrounding it, as shown, which permits the type-bar to enter the slot and prevents dirt from flying while brush is in operation.

As stated before, the brush is rigidly secured to the spirally-grooved shaft 26 near its end. Now when the nut is moved outwardly it will carry the shaft 26 with it until the front end of said shaft 26 strikes the upturned forward part of the rod. If now the outward movement of the nut is continued 20 the shaft will be caused to rotate in one direction and the brush rotates with it, the brush having been carried by the forward movement of the shaft toward the front wall of the casing. The coil - spring surrounding the shaft 26 will also be compressed by this 25 movement of the nut 28. Now if the forward pressure on the nut be released the spring will force the nut rearwardly and cause a reverse revolution of the shaft and brush 30 and also cause the shaft to move axially rearwardly until the rear pintle end of the shaft engages the rear wall of the casing, said wall forming a bearing for said pintle end of the shaft. It will thus be seen that the brush is 35 revolved alternately in opposite directions and also has a considerable axial range of movement. These movements of the brush will result in a thorough cleaning of both the upper and lower case letters on the end of the 40 type-bar, which are brought into the slot of the casing and held there while being cleaned.

The bar 21 may be slotted, if desired, and the nut 28 provided with a projection fitting in such slotted rod and guided therein. The 45 said bar 21 may also be provided with an extensible attachment 31, as shown in Figs. 5 and 6, adapting the device for use on various sizes of machines.

In applying the device the carriage of the 50 type-writing machine is thrown upwardly and backwardly out of the way. The tongue 18 of the rear wall 16 of casing 14 is now placed under the front end of the ribbon and the ribbon pushed backwardly from the 55 point in the type-well where the type center strikes. The curved front end of the rod 21 is now brought down and fits on the shift-rail 11, the slot in the end of rod 21 fitting over the block 12, as stated, to prevent lateral 60 movement of the device. If now the keys are struck, the type-bars will be swung upwardly and the type ends enter the slot 17 of the casing, where they are held while the spiral nut is moved backwardly and for-

wardly on the guide-rod 21, causing the shaft 65 26 to rotate and the brush to have a reciprocal rotary movement and also an axial movement, thus perfectly cleaning the type. It will be observed that one hand is free to manipulate the keys, while the other is used 70 to operate the cleaning device.

As shown in Figs. 5 and 6, the extension-piece 31 may be provided with a slot 32, by means of which and bolt and nut 33 and 34 it may be moved back and forth upon bar 21. 75 The upper surface of the curved hook 23 is grooved to permit the back-and-forth adjustment of slotted bar 21 and also prevents lateral movement of said slotted bar; but I do not wish to confine myself to such construction, as said extension-piece may be made in any practical manner to fit the various makes of type-writing machines, and, furthermore, the parts of the improved cleaning device may be so arranged as to permit it 80 to be applied to the rear of a type-writing machine where the peculiar construction of the machine would render its location necessary at that place.

Having thus described my invention, what 90 I claim as new, and desire to secure by Letters Patent, is—

1. A type-cleaning device for type-writing machines consisting of a brush, a shaft upon which said brush is secured, and means slidably engaging the shaft for alternately rotating said shaft said means also causing an axial movement of said shaft. 95

2. A type-cleaning device for type-writing machines, consisting of a casing, means projecting from said casing to engage and push away the ink-ribbon from the path of the type-heads, a brush within said casing, a shaft upon which said brush is rigidly mounted, and means engaging the shaft for imparting a 100 reciprocal rotary movement of said shaft. 105

3. A type-cleaning device for type-writing machines consisting of a casing, means projecting from said casing, adapted to engage and push away the ink-ribbon from the path 110 of the type-bar heads, a brush within said casing, a spirally-grooved shaft mounted in said casing and carrying said brush, a guide-bar extending forwardly from said casing and supporting the spirally-grooved shaft at its 115 front end, a spirally-bored nut fitting said shaft and engaging the guide-bar, whereby a longitudinal reciprocating movement of the nut on said shaft will cause a reciprocal rotary movement of the brush. 120

4. A type-cleaning device for type-writing machines consisting of a casing, a spirally-grooved shaft mounted in said casing and extending through the front wall thereof, a brush rigidly mounted on said shaft within the casing, a guide-bar extending forwardly from the front wall of said casing adjacent to the spirally-grooved shaft, and having near 125

- its front end a bent portion supporting the front end of the shaft, a spirally-threaded nut mounted on the shaft and engaging the guide-bar, a spring held between the nut and the support of the front end of shaft, a hook at one end of the guide-bar adapted to engage the guide-rail of the type-writing machine, and means for reciprocating the nut on the shaft causing a reciprocal rotary movement of the brush.
5. A type-cleaning device for type-writing machines consisting of a casing having an elongated slot in its lower wall, a removable rear wall, a spirally-grooved shaft mounted in said casing and extending through the front wall thereof, a brush rigidly secured to said shaft near its rear end, a guide-bar extending forwardly from the front wall of said casing adjacent to the spirally-grooved shaft, said guide-bar being bent near its front end downwardly then upwardly and having a hooked front end, said downwardly-bent portion having an opening through which the forward end of the spirally-grooved shaft passes, a spirally-threaded nut mounted on said shaft and snugly fitting the same, and means for reciprocating the nut to first cause an axial movement of the shaft and then a rotary movement of the same.
10. 6. A type-cleaning device for type-writing machines consisting of a brush, a shaft to which said brush is secured, said shaft having a spiral groove of rapid pitch, a frame in which said shaft is mounted to rotate and also reciprocate longitudinally, and a spirally-bored nut adapted to fit the shaft snugly, whereby longitudinal movement of the nut will cause the shaft to reciprocate longitudinally and to rotate.
15. 7. A type-cleaning device for type-writing machines consisting of a casing, a brush within said casing, a shaft mounted in said casing and carrying said brush, an extensible guide-bar extending from said casing, and supporting the shaft at its end, a nut slidably fitting 45 said shaft and engaging the guide-bar, said shaft and nut being provided with coacting instrumentalities whereby a longitudinal reciprocating movement of the nut on the shaft will cause a reciprocal rotary movement of 50 the brush.
8. A type-cleaning device for type-writing machines, consisting of a casing, a spirally-grooved shaft mounted in said casing and extending through the front wall thereof, a brush rigidly mounted on said shaft within the casing, a guide-bar extending forwardly from the front wall of said casing adjacent to the spirally-grooved shaft and having at or near its front end a bent portion supporting 55 the front end of the shaft, a spirally-threaded nut mounted on said shaft, a hook at one end of the guide-bar adapted to engage the guide-rail of the type-writing machine, and means for reciprocating the nut on the shaft to cause 60 a reciprocal rotary movement of the brush.
9. A type-cleaning device for type-writing machines, consisting of a casing, a spirally-grooved shaft mounted in said casing and extending through the front wall thereof, a brush rigidly mounted on said shaft within the casing, a guide-bar extending forwardly from the front wall of said casing adjacent to the spirally-grooved shaft and having at or near its front end a bent portion supporting 65 the front end of the shaft and permitting longitudinal play thereof, a spirally-threaded nut mounted on said shaft, and means for reciprocating the nut on the shaft causing reciprocating movement of the shaft and a reciprocal rotary movement of the shaft and brush.
